UNITED STATES PATENT OFFICE

137,623

DESIGN FOR AN AIRPLANE

George A. Page, Jr., Creve Coeur, Mo., assignor to
Curtiss-Wright Corporation, a corporation of
Delaware

Application January 29, 1943, Serial No. 109,363

Term of patent 14 years

(Cl. D71—1)

To all whom it may concern:

Be it known that I, George A. Page, Jr., a citizen of the United States, residing at Creve Coeur, in the county of St. Louis, State of Missouri, have invented a new, original, and ornamental Design for Airplanes, of which the following is a specification, reference being had to the accompanying drawings forming a part thereof.

In the drawings,

Fig. 1 is a top plan view of an airplane showing my new design;

Fig. 2 is a side elevational view of the airplane;
Fig. 3 is a front elevational view of the airplane;

Fig. 4 is a three quarter perspective view of the airplane in flight, looking upwardly from below.

I claim:

The ornamental design for an airplane, substantially as shown.

GEORGE A. PAGE, JR.
